(57) **CLAIM**

The ornamental design for a slow feed bowl, as shown and described.

DESCRIPTION

FIG. 1 is a front, top isometric view of a slow feed bowl in accordance with our new design;

FIG. 2 is a front elevation view thereof, the rear elevation is identical;

FIG. 3 is a right side elevation view thereof, the left side elevation is identical;

FIG. 4 is a top plan view thereof;

FIG. 5 is a bottom plan view thereof;

FIG. 6 is a cross-sectional view taken along and in the direction of line 6-6 in FIG. 4;

FIG. 7 is a cross-sectional view taken along and in the direction of line 7-7 in FIG. 4;

FIG. 8 is another isometric view thereof; and,

FIG. 9 is another isometric view, but shown in a usage state in an environment view.

The broken lines shown in FIG. 9 illustrate environmental structure that form no part of the claimed design.

1 Claim, 7 Drawing Sheets
